HIGH CAPACITY MINE CAR

Robert A. Shields, Berwick, Pa., assignor to
American Car and Foundry Company, New
York, N. Y., a corporation of New Jersey

Application March 22, 1939, Serial No. 263,336

16 Claims. (Cl. 105—364)

1

This invention relates to railway cars in general and in particular to mine or industrial cars of the high capacity type.

The majority of mine cars have in the past been constructed with a heavy traction frame which of itself was sufficiently strong to carry the entire lading load for which the car was designed. This heavy frame had attached thereto the box like structure intended to retain the lading and transmit the load to the frame. It was, of course, necessary to brace the box like structure and make it sufficiently strong to carry the lading and load to the frame, which resulted in a car far stronger than necessary and with the metal placed so that its full value was not developed. Certain of these cars were many times too strong in certain places, while being barely strong enough in others to carry the load and in practically all cases were extremely rough on the interior, presenting a large number of rivet heads, sill flanges, braces and other obstructions to the ready discharge of the lading. It is of prime importance that a mine car have the interior as smooth as possible for the finely divided coal sifts to the bottom or is washed there by the water loaded with the coal and packs in the bottom against any obstruction to such an extent that it becomes rock like and almost impossible to remove. It is an object, therefore, of the present invention to provide a mine car having a smooth interior for the ready discharge of lading and to eliminate projections against which finely divided coal or other material may pack.

A further object of the invention is the provision of a mine car constructed mainly of plate metal and without the use of separate sill members but with substantially box section longitudinal stiffeners formed by integral parts of the car structure.

A still further object of the invention is the provision of a mine car or other industrial car having substantially box section longitudinal stiffeners intermediate the side walls and formed by overlapping flanges of the floor plates, thus causing the metal to serve both a load carrying and load retaining function.

A still further object of the invention is the provision of a mine car of simple construction in which full value is obtained from the component metal parts, thus giving a car of maximum strength and capacity with a minimum of weight.

These and other objects of the invention will be apparent to persons skilled in the art from a study of the following description and accompanying drawings, in which:

2

Figure 1 is an elevational view of substantially one-half the car;

Fig. 2 is a sectional view of the other half of the car and when taken with Figure 1 shows the complete car;

Fig. 3 is a plan view of substantially the half car shown in Fig. 2;

Fig. 4 is an end view of the car with one-half being shown in section substantially at the axle plane;

Fig. 5 is an enlarged sectional view taken substantially on line 5—5 of Figure 1;

Fig. 6 is an elevational view of one end of a modified form of car with parts broken away to better show the end construction;

Fig. 7 is an inverted plan view of the modified car shown in Fig. 6;

Fig. 8 is an enlarged sectional view taken substantially on line 8—8 of Fig. 6;

Fig. 9 is an enlarged sectional view taken substantially on line 9—9 of Fig. 6, and

Fig. 10 is an enlarged sectional view showing a modified form of longitudinal stiffener construction which may be used either with the construction shown in Figures 1 to 5 inclusive or in Figures 6 to 9 inclusive.

Referring now to the drawings in detail and in particular to Figures 1 to 5 inclusive, it will be seen that the car has been constructed with the floor as low as possible and with the car body supported on stub axles, although it will be obvious that the car may be supported on through axles or that the side portions may be carried at a different level than the center or main floor section. As shown the car is constructed with a central or main floor section 2, having its side edges flanged upwardly as at 4, then laterally outward as at 6, thus forming a pair shaped central section with the ends open. The side wings or side lading portions of the car are formed by plate metal sections 8, having their outer side edges flanged upwardly as at 10, while their inner side edges are flanged upwardly as at 12, then laterally inward as at 14. The upwardly directed flanges 12 are in the present instance made of sufficient depth to permit the flange 14 to overlap the flange 6 of the central section while retaining the wing portions 8 and central floor section 2 in a substantially common plane. The overlapping flanges 14 and 6 are suitably secured together either by riveting or welding, although the latter is preferable since it presents a smoother surface to the lading. It will thus be seen that a substantially box section longitudinal stiffener is formed by the vertical

flanges 4 and 12 and horizontal flanges 6 and 14 of the center and side sections respectively. The maximum strength of this box section may be developed by closing the bottom thereof but in practice it has been found sufficient in most cases to attach tie plates 16 at frequent intervals closing the bottom of the box and tying the center and side sections together. The side sections have openings cut therein to receive the wheels W and these wheels may be mounted on through axles or on stub axles 18 as shown. The ends of the stub axles support inner boxes 20 inserted within the box section stiffener and acting not only as a car support, but also as a tie between the flanges 4 and 12, since the box is rigidly attached within the box section by rivets or bolts 21, thus materially strengthening the stiffener or sill member at the area of greatest load concentration. This journal box placement of necessity causes upright portions of the stiffener or sill member to be intersected by the stub axles and preferably these upright portions are located close to the wheel hoods, as clearly shown. The outer ends of the stub axles support outer journal boxes 22 riveted or otherwise attached to a load distributing structure 24. A portion of the load distributing structure is preferably of Z section having the lower flange 25 attached to the side section 8 and with the web extending vertically, while the top flange 26 is directed inwardly for support upon the outer journal box and to provide a ledge upon which the wheel hood 28 may rest and be secured by any suitable means. The Z member is bent to provide an end and outer side adjacent each wheel, while the other side is closed by a gusset plate 30 flanged at its lower edge as at 31 for attachment to the side floor section and secured to the Z member by vertically extending angle 32. The inner portion of the gusset is reduced in height and extends horizontally into contact and attachment with the flange 12 of the box section stiffener and has attached thereto at the upper edge an angle 33 with the one leg located in the plane of the flanges 14 and 26. It will thus be seen that the load distributing structure consists of a box like arrangement formed of a Z and gusset plate rigidly attached to the box section stiffener and enclosing the wheel and distributing the load from the side floor section to the outer journal box.

The outer edges of each gusset 30 are attached to angle stakes or stiffeners 34 secured to the side wall 36 which is attached at its lower edge to the flange 10 of the side floor section, while the top is deflected inwardly and upwardly for attachment to a Z section top chord 38. The ends of the side sheets are rigidly attached to the car end walls 40 in any suitable manner and the top edges of the end sheets are preferably reinforced by angle structures 42 which in effect continue the side top chords 38 across the ends of the car. The end walls are, of course, rigidly connected not only to the side walls, but also to the side floor sections, longitudinal stiffeners or sill members and to the center floor section by the bumper and draft housings of any suitable construction. As clearly shown in Figures 1, 2, 3 and 4 the end bumper and draft housings are formed of a substantially flat bottom plate 44 flanged upwardly at its side edges as at 45 (Fig. 4) for attachment by means of an angle 46 to the top plate 48, which top plate has its inner edge deflected downwardly as at 49, thence rearwardly as at 50 for attachment to the bottom

plate 44 and the center floor section. As clearly shown in Fig. 3 the bottom plate 44 and the main portions of the top plate are extended beyond the center section in order that the flanges 5 45 may be riveted directly to the flanges 12 of the outer floor sections, while the vertical flange 49 of the top plate may abut the ends of the flanges 4 and 6 of the center floor section. It will thus be seen that in this manner a strong connection is made between the bumper and drawhead housing and the longitudinal stiffener or sill member with the housing backed up by the entire center floor section to receive buffing forces which are the maximum transit shocks to which a car is subjected. The housing may receive any type of bumper and drawhead construction desired, but in the present instance a double acting spring bumper and drawhead 52 has been shown as inserted within the housing and held in place by vertical bolts 53.

The central floor section is stiffened intermediate the bumper and drawhead housings by means of angles 54 placed with the edges of the legs in contact with the floor section 2 for attachment thereto by welding or other means. The ends of these angles are also welded or otherwise attached to the vertical flange 4 of the center floor section and will, due to the inner journal box, form a ready tie between the entire box section stiffeners at either side of the car, thus in effect continuing the stub axles across the center floor section, while at the same time preventing any sagging thereof. It will be seen that the longitudinal stiffeners or sill members together with their reinforcements carry a portion of the load to the stub axles, while a portion of the load will be carried by the end walls and side walls through the gussets of the load distributing structure to the wheels. In this manner substantially every component part of the car structure serves to retain the lading in position and to carry the load of the lading to the wheels and axles. It will also be seen that a large capacity car has been provided with substantially the entire floor area at a low plane below the level of the axles and with a minimum of projections into the lading zone. Each of the necessary projections into the lading zone present a smooth surface to the lading eliminating pockets or other obstructions to the discharge of lading as the car is dumped.

Referring now to the modified car shown in Figs. 6 to 9 inclusive it will be seen that the center floor section 60 is formed at the central part thereof with a car haulage channel 62 adapted to receive therein a car haulage lug 63. The side edges of the center floor section are flanged upwardly as at 64, then outwardly as at 65. The vertical flanges 64 are pierced in order to receive the through axle 66 which supports the box 68 and in turn is supported by the car wheels W. In this car the side floor sections are provided with two levels, one at each end substantially in alignment with the center floor section and one at the central zone at a level substantially parallel to the flanges 65 of the center floor section. The end side floor sections 70 have their inner edges flanged upwardly as at 71, thence inwardly as at 72 to underlie the flanges 65 of the center floor section. Suitable cross ties 73 join the end side sections and center floor sections, thus tying the box section longitudinal stiffeners or sill members together by attachment of flanges 65 and 72. The intermediate or higher level side floor section 75

has the inner edge flanged downwardly as at 76 to overlap and be secured to the flange 64 of the center section, thus forming a strong stiffener between the box section ends and a convenient arrangement for attachment of the boxes 68 previously referred to. As shown in the present construction the flange 65 of the center section has been burned away in the area occupied by the floor section 75, but it is, of course, obvious that this side section may be lowered slightly and placed beneath the flange 65 if it is so desired. The end edges of the central side floor section are supported by angles 76 attached to gussets 80 which in turn are rigidly connected to the car side wall and to the flanges 64 and 71 of the center and end side sections respectively. The lower edges of these gussets are flanged as at 82 to underlie and support the inner edges of the end side floor portions as clearly shown in Figs. 7 and 8. It will thus be seen that the gussets tie the side walls to the longitudinal stiffeners or sill members and support the edges of both the intermediate and end side floor portions, while at the same time serving as a tie between the flanges 71 and 64 of the box section longitudinal stiffener. It will also be seen that any loads picked up by the short box section stiffeners will be transmitted at least in part through the gusset to the stiffener flanges 64 and 76 which will in turn carry the loads to the wheels and axles. The intermediate side floor sections have a part thereof cut out in order to permit rotation of the wheels and withdrawal of the same from the axle and such openings are covered by wheel hoods 84 attached to the longitudinal stiffeners, intermediate side floor section and car side wall. The car wall 86 in the instance shown extends between the end walls 87 to which they are rigidly attached and has its lower edge flanged as at 88 to support the outer edges of both the end and intermediate side floor sections. The upper edge of the car side walls is stiffened and reinforced by an angular top chord formed by an upwardly inclined portion 89 joined by a roll 90 to a vertical flange 91, which in turn is integral with a horizontal flange 92 and vertical flange 93. The flange 93 overlaps and is spaced from the edge of the inclined portion 89 and is adapted to receive therebetween the upper edge of the side sheets to which they are attached by any suitable means such as welding.

Any desirable form of bumper and drawhead housing may be used, but in the present instance this housing is formed by a lower Z shaped plate 95 and an upper distorted Z section plate 96 joined together directly at their rear edges and intermediate their edges by an angle plate 97. This structure is attached to the horizontal portion of the center floor section as well as to the flanges 64 thereof and carries any suitable type of bumper arrangement 98.

The center floor section is stiffened by means of tie plates 99 welded to the section 60 and flange 64 of the center floor section and having its ends extended as at 100 for attachment to the side floor sections and gusset 80. It will thus be seen that a portion of the floor loads will be directly carried to the journal boxes, while other portions will be carried by the side walls through gussets 80 to the longitudinal stiffeners and cross ties which will in turn distribute the load to the car axles. The gussets and cross ties also serve to prevent bulging of the car side walls or sagging of the center floor section and also prevent any distortion of the longitudinal stiffeners under

load. In this car as in the car previously described, it will be seen that each component part serves not only to retain the load in position but to transfer the weight of such load to the axles for support by the wheels.

It will, of course, be obvious that if desired the side floor section may be located at a single level above the center floor section, in which case the angular form of stiffener present between the axles will be extended completely to the end of the car. It may be desirable under some circumstances to provide additional strength between the axles, in which case the intermediate side floor section 75 may be flanged downwardly as at 110 (Fig. 10) thence inwardly as at 112, thus providing in effect a box section longitudinal stiffener throughout the length of the car. The flanges 65 and 112 may be securely attached by any suitable means, such as welding, but prior to such attachment the boxes 114 will be attached securely to the flanges 64 and 65 of the center floor section. In this form the gussets 80 previously referred to will, of course, occupy their same position, while the flanges 110 will abut such gussets and be attached thereto, thus in effect making the flanges 71 and 110 continuous throughout the length of the car. It will, of course, be obvious that if it is desired that the entire side floor section be carried at the same level the construction shown in Fig. 10 is extremely suitable and will give a complete box section longitudinal stiffener throughout the length of the car. It will also be obvious that such an arrangement is equally applicable to the constructions shown in Figs. 1 to 5 since it is only necessary to turn the side floor sheet end for end to obtain the construction shown in Fig. 10, although in turning the side floor sections it may be desirable to either eliminate the flange 10 or turn such flange in the opposite direction to receive the side wall sheets.

It will be obvious from the preceding descriptions of the various constructions that in every instance a smooth interior is provided for the car and that substantially all parts are made of plate metal securely attached together and so formed that the full value of the metal is developed. In other words, each part of the car serves not only to retain the lading in position, but also to transfer the load of such lading to the wheels. It will be equally obvious that various modifications in form and arrangement of parts other than those described will suggest themselves to persons skilled in the art, but all such modifications and rearrangements of parts are contemplated as will come within the scope of the following claims which define my invention.

What is claimed is:

1. In a mine or other industrial car having side walls and end walls the combination of a pan-shaped central floor portion, substantially pan-shaped side floor portions adjacent each side edge of said central floor portion, said pan-shaped floor portions extending substantially continuously from end wall to end wall of the car and having their adjacent side edges secured together in spaced relationship by means joined to the upper edges of the adjacent side edges and closing the space therebetween to thereby form the entire floor of the car as well as upwardly projecting substantially box-section longitudinal stiffeners extending substantially continuously from end wall to end wall of the car and forming the main longitudinally extending load carrying element located between the side walls.

2. In a mine or other industrial car supported on spaced wheels and axles the combination of a pan shaped central floor portion, substantially pan shaped side plate floor portions adjacent each side edge of said central floor portion, said pan shaped floor portions being secured together along their adjacent edges by means holding the sides of the pan shaped portions in spaced relationship, said means closing the space between the sides and being joined to the upper edges of the sides to thereby simultaneously form the floor of the car as well as substantially continuous box section longitudinal stiffeners, and journal boxes secured within said box-section stiffeners and adapted to receive the axles for supporting the car, said journal boxes cooperating with said means in connecting and holding the sides of the pan shaped floor portions in spaced relation thereby mutually bracing each other.

3. In a mine or other industrial car the combination of a central floor portion, side floor portions adjacent each side edge of the central floor portion, upwardly extending flanges formed on the adjacent edges of said floor portions, and reflanges formed on the free edges of said flanges, said reflanges being directly secured together to hold said flanges in spaced relationship and to simultaneously form the car floor and substantially box-section longitudinal stiffeners therefor, said reflanges overlapping each other to produce a double thickness of material acting in tension on the upper edge of said box section stiffeners to thereby reinforce the same.

4. In a mine or other industrial car supported on spaced wheels and axles and having spaced end walls the combination of a central floor portion extending substantially from end wall to end wall of the car, side floor portions adjacent each side edge of the central floor portion, flanges formed on the adjacent edges of said floor portions and between said wheels, and means directly securing said floor portions together to simultaneously form the car floor and longitudinal stiffeners therefor, which stiffeners are integral with the floor portions and extend substantially continuously from end wall to end wall of the car, said means retaining at least portions of said flanges in spaced relationship, thereby forming at least portions of said stiffeners of box-section.

5. In a mine or other industrial car the combination of a central floor portion having upwardly directed flanges on the side edges thereof, side floor portions adjacent each side edge of the central floor portion, upwardly directed flanges on the side edges thereof, means joining the adjacent upwardly directed flanges together to simultaneously form the car floor and integral longitudinal stiffeners therefor, said means retaining at least portions of said flanges in spaced relationship thereby forming at least portions of said stiffeners substantially of box-section, journal boxes secured within the box section portion of said stiffeners and additionally securing said flanges together, and axles supporting said journal boxes and located at least in part above said floor.

6. In a mine or other industrial car having side walls the combination of a central floor portion having upwardly directed flanges on the side edges thereof, side floor portions adjacent each side edge of the central floor portions, said side floor portions having the ends thereof located substantially in the plane of the central floor portions and formed with upwardly directed flanges, the intermediate portion of said side floors being

located in a plane spaced upwardly from the plane of the central floor portion and formed with downwardly directed flanges, and means joining all of the adjacent flanges together to simultaneously form the car floor and longitudinal stiffeners therefor.

7. In a mine or other industrial car having side walls the combination of a central floor portion having upwardly directed flanges on the side edges thereof, side floor portions adjacent each side edge of the central floor portions, said side floor portions having the ends thereof located substantially in the plane of the central floor portions and formed with upwardly directed flanges, the intermediate portion of said side floors being located in a plane spaced upwardly from the plane of the central floor portion and formed with downwardly directed flanges, means joining all of the adjacent flanges together to simultaneously form the car floor and longitudinal stiffeners therefor, and gussets joined to said side walls and joining the end and intermediate portions of said side floor portions.

8. In a mine or other industrial car having side walls the combination of a central floor portion having upwardly directed flanges on the side edges thereof, side floor portions adjacent each side edge of the central floor portions, said side floor portions having the ends thereof located substantially in the plane of the central floor portions and formed with upwardly directed flanges, the intermediate portion of said side floors being located in a plane spaced upwardly from the plane of the central floor portion and formed with downwardly directed flanges, means joining all of the adjacent flanges together to simultaneously form the car floor and longitudinal stiffeners therefor, and gussets joined to said side walls and joining the end and intermediate portions of said side floor portions, said gussets being also joined to the flanges of said end and intermediate side floor portions and to the flanges of said central floor portion.

9. In a mine or other industrial car having side walls the combination of a central floor portion having upwardly directed flanges on the side edges thereof, side floor portions adjacent each side edge of the central floor portions, said side floor portions having the ends thereof located substantially in the plane of the central floor portions and formed with upwardly directed flanges, the intermediate portion of said side floors being located in a plane spaced upwardly from the plane of the central floor portion and formed with downwardly directed flanges, means joining all of the adjacent flanges together to simultaneously form the car floor and longitudinal stiffeners therefor, and gussets joined to said side walls and joining the end and intermediate side floor flanges in abutting relation and joining the end side floor portion flanges and central floor flanges in spaced relation thereby forming the ends of the stiffeners of box section, and gussets joining the end and intermediate side floor portions to the side walls, said gussets also closing the inner ends of the box-section portions of the stiffeners and connecting the same to the intermediate side floor flanges.

10. In a mine or other industrial car having side walls the combination of a central floor portion side floor portions adjacent each side edge of the central floor portion, flanges formed on the adjacent edges of said floor portions, means securing said floor portions together with the flanges held in spaced relationship to simultane-

ously form the car floor and integral substantially box-section stiffeners therefor, journal boxes secured within the box-section stiffeners and mutually bracing each other, load distributing structures secured to said stiffeners, to said side floor portions and to said side walls, additional journal boxes secured to load distributing structures, stub axles supporting said journal boxes, wheels on said stub axles, and wheel hoods connected to the box-section stiffeners and load distributing structures.

11. In a mine or other industrial car having side walls the combination of a central floor portion, side floor portions adjacent each side edge of the central floor portion, flanges formed on the adjacent edges of said floor portions, means securing said floor portions together with the flanges held in spaced relationship to simultaneously form the car floor and substantially box-section stiffeners therefor, journal boxes secured within the box-section stiffeners and mutually bracing each other, load distributing structures secured to said stiffeners, to said side floor portions and to said side walls, additional journal boxes secured to load distributing structures, stub axles supporting said journal boxes, wheels on said stub axles, wheel hoods connected to the box-section stiffeners and load distributing structures, and cross ties of inverted angle form connected to the central floor portion and box-section stiffeners and positioned substantially in alignment with the stub axles.

12. In a mine or other industrial car having side walls the combination of a central floor portion, side floor portions adjacent each side edge of the central floor portion, flanges formed on the adjacent edges of said floor portions, means securing said floor portions together with the flanges held in spaced relationship to simultaneously form the car floor and integral substantially box-section stiffeners therefor, said box-section stiffeners forming the main longitudinally extending load carrying elements between the side walls, load distributing structures located wholly above the floor level and secured to said stiffeners and to said side floor portions, outer journal boxes secured to said load distributing structures, inner journal boxes secured to said box section stiffeners, stub axles located wholly above the floor level formed by said central and side floor portions and supporting said journal boxes, wheels carrying said axles and projecting through said side floor portions, and wheel hoods connected to the box-section stiffeners and load distributing structures.

13. In a mine or other industrial car having side walls the combination of a central floor portion, side floor portions adjacent each side edge of the central floor portion, flanges formed on the adjacent edges of said floor portions, means securing said floor portions together with the flanges held in spaced relationship to simultaneously form the car floor and substantially box-section stiffeners therefor, said box-section stiffeners forming the main longitudinally extending load carrying elements between the side walls, load distributing structures secured to said stiffeners and to said side floor portions, outer jour-

nal boxes secured to said load distributing structures, inner journal boxes secured to said box-section stiffeners, stub axles supporting said journal boxes, wheels carrying said axles and projecting through said side floor portions, wheel hoods connected to the box-section stiffeners and load distributing structures, gussets comprising a part of said load distributing structures and connecting the side walls and box-section stiffeners, and cross ties joined to certain of said flanges and central floor portions to prevent distortion of the floor and to form in effect a continuation of the stub axles transversely of the car.

15 14. In a mine or other industrial car having side walls the combination of a central floor portion, side floor portions adjacent each side edge of the central floor portion, flanges formed on the adjacent edges of said floor portions, means securing said floor portions together with the flanges held in spaced relationship to simultaneously form the car floor and substantially box-section stiffeners therefor, portions of the flanges of said central floor portion being cut away whereby the box-section terminates inwardly of the car end, and end structures secured to the central floor portion and to the flanges of said side floor portions, said end structures overlappingly abutting and being secured to the ends of said flanges of the central floor portion thereby closing the ends of the box-section stiffeners and bracing the end structures.

15 15. In a mine car, wheels and individual wheel supporting stub axles at each side of the car, wheel hooding structures overlying the wheels, means supported on each stub axle, a sill member extending longitudinally of the car along each side of the car, each said sill member including an upright wall portion disposed at least in part beneath the horizontal plane occupied by the wheel axes and so close to the adjacent wheels as to lie in a vertical plane which intersects the stub axles at that side of the car, and a central lading bottom substantially closing the space between the sill members, said means supported on each stub axle being carried in part by a sill member and in part by other parts of the car structure.

16 16. In a mine car, car wheels and individual wheel supporting stub car axles at each side of the car, wheel hooding structures closely overlying the car wheels and with inside longitudinal closure walls close to adjacent wheels, stub axle supporting means, longitudinally extending sill-elements inside oppositely disposed car wheels and forming at least partial support for the said supporting means, each said sill-element including an upwardly extending wall portion disposed at least in part beneath the horizontal plane occupied by the wheel axes and located so close to adjacent wheels as to lie in a substantially vertical plane which intersects the stub axles at that side of the car, and a central lading bottom lying at least in part below the horizontal plane of the axes of the car wheels and substantially closing the space between the sill members.

ROBERT A. SHIELDS.
